UNITED STATES PATENT OFFICE.

WILLIAM FREDRICK WEBBER, OF HORNELLSVILLE, NEW YORK.

WIRE FENCE.

SPECIFICATION forming part of Letters Patent No. 460,316, dated September 29, 1891.

Application filed December 26, 1890. Serial No. 375,785. (No model.)

To all whom it may concern:

Be it known that I, WILLIAM FREDRICK WEBBER, of Hornellsville, in the county of Steuben, in the State of New York, have invented new and useful Improvements in Wire Fences, of which the following, taken in connection with the accompanying drawing, is a full, clear, and exact description.

My invention relates to strands used in constructing wire fences.

My object is to produce such a strand cheap and very durable in construction and of great utility.

My invention consists in the several features of construction hereinafter described, and which are set forth in the claim hereto annexed.

The drawing shows a horizontal side elevation of my fence-strand to a vertical position.

20 A A are main or supporting parallel wires of the strand, provided with lateral or inward projecting corrugations 1 1 at regular distances apart, and are preferably opposite each other, although it will readily be observed 25 that they may be at irregular distances apart and not opposite without departing from the spirit of my invention.

22 are zigzag wires extending, as shown,

from one of the main wires to the other and crossing each other at 3. It will be observed 30 that one of these zigzag wires passes up and over the recess 1 1 of the main wire and down the other side, and that the other zigzag wire takes an opposite direction, thereby forming a very strong and durable strand. It will also 35 be observed that I may embed either laterally or vertically the main wires, so that in weaving in the zigzag wires much labor may be saved and the size of the mesh will always be maintained, for the reason that the wires woven 40 in cannot slide out of place. In the drawing I show but two wires; but it will be apparent that any number may be used.

What I claim as my invention, and desire to secure by Letters Patent, is— 45

A wire-fence strand consisting of two parallel wires, each having a series of bends or recesses, and zigzag wires crossing each other and engaging with said bends, as set forth.

In witness whereof I have hereunto set my 50 hand on this 22d day of December, 1890.

WILLIAM FREDRICK WEBBER.

In presence of—

FRANK KELLY,
ALFRED WEBB.
